UNITED STATES PATENT OFFICE.

GEORGE H. KLUMPH AND JAMES E. HOUSTON, OF CHICAGO, ILLINOIS.

WATER-HEATER.

1,107,313.

Specification of Letters Patent. Patented Aug. 18, 1914.

Application filed July 31, 1913. Serial No. 782,207.

To all whom it may concern:

Be it known that we, GEORGE H. KLUMPH and JAMES E. HOUSTON, citizens of the United States, residing at Chicago, in the county of Cook and State of Illinois, have invented certain new and useful Improvements in Water-Heaters, of which the following is a specification.

This invention relates to water heaters of the water tube type, the object of the invention being to increase the efficiency of such water heaters. This object we attain by mechanically imparting to the water flowing through the heater a velocity greater than that due to the pressure of the source of supply, such increased velocity resulting in a greater absorption of heat from the furnace gases. In order to obtain such increased velocity, we have provided means for recirculating the water within the heater and before the water leaves the heater.

In the accompanying drawings, Figure 1 is a top plan view of one embodiment of our invention, Fig. 2 is an end elevation looking from the right-hand side of Fig. 1. Fig. 3 is a perspective view of one of the units composing the heater. Fig. 4 is a simplified diagrammatic view illustrating the course taken by the liquid while flowing within and through the heater.

While the invention is susceptible of various embodiments, we have herein shown it as embodied in a fuel economizer which, in most respects, is of standard form. For the sake of clearness of understanding we shall refer to specified numbers of pipes, etc., but it will be understood that the invention may be embodied in an economizer or other heater of any desired size.

The economizer, proper, is composed of a plurality of sections each substantially similar to the one illustrated in Fig. 3. Each section consists of a top box or header 1, a bottom box or header 2 and a plurality of vertical pipes 3 connecting the top box and the bottom box. The sections are compactly grouped side by side as represented in Fig. 1. The economizer may be located in any convenient relation to the steam boiler and the smoke stack, with provisions to cause the gases of combustion to flow through the spaces among the pipes 3. For the sake of simplicity, the inclosing casing has been omitted in the drawings. A partition or baffle 4 extends transversely of all of the top boxes 1, preferably midway the length of

said boxes. Two manifold pipes 5 and 6 extend longitudinally of the series of economizer sections and are connected with the opposite ends of the top boxes 1 by means of short pipes 7. A manifold pipe 8 extends longitudinally of the series of economizer sections and is connected to one end of each of the bottom boxes 2. Partitions or baffles are located in the manifold pipes 5, 6 and 8 at the points indicated in Fig. 1 at 9, 10, 11 and 12. The water to be heated is admitted to the manifold pipe 5 at 13. Entering the top boxes of the four sections that are located between the inlet 13 and the partition 9, the water flows downwardly through the sixteen pipes 3 located at the inlet side of the partition 4 (that is to say, between said partition and the manifold pipe 5); passes to the bottom boxes and upwardly through the sixteen pipes 3 at the opposite side of the partition 4 and flows thence into the manifold pipe 6, filling the last mentioned pipe up to the partition 11. The water also fills the economizer sections located between the partitions 9 and 12 on the one side and the partitions 10 and 11 on the other side. When passing to the outlet, the water leaves said sections through the lower manifold pipe 8 and flows to the sections located to the left (Fig. 1) of the partitions 10 and 11. The water flows upwardly from the bottom boxes of the last mentioned sections through the pipes 3 of said sections into the manifold pipes 5 and 6. The water passes from the manifold pipe 5, through a pipe 14, and thence to the outlet 15.

The economizer may be considered to consist of three divisions, the first division being composed of the sections located between the inlet 13 and the partition 9, the second division consisting of the sections located between the partitions 9, 10 and 11, and the third division consisting of the sections located between the partitions 10 and 11 and the outlet 15. These divisions are indicated in Fig. 1 by the reference letters A, B and C, respectively. The divisions A, B, and C may be of any suitable relative dimensions, the inlet and outlet divisions A and C preferably being quite small as compared with division B. In the embodiment illustrated in Fig. 1, division B has been considerably shortened by reason of limitations of space for illustration. Water is supplied to the inlet 13 from any well-known or preferred source of supply under pressure, such

as an elevated tank, a city main, or a pump (not shown).

In order to obtain an increase in velocity of the water contained in division B over that which is caused by the source of supply, we provide means for positively circulating the water within division B, *i. e.*, for drawing water from division B and returning it to said division. The circulating means may be of any suitable character. Herein we have illustrated a pump 16 which may, if desired, be of the centrifugal type, as shown. The inlet side of said pump is connected with that portion of the manifold pipe 6 which connects with the sections forming division B by means of a pipe 17. The discharge side of the pump 16 is connected to the manifold pipe 5 at a point between the partitions 9 and 10, by means of a pipe 18. The pump 16 may be driven in any preferred manner as by means of an electric motor 19. It will be seen that the warm water contained in that portion of division B which is located between the partition 4 and the manifold pipe 6 will be drawn by the pump 16 through the pipe 17 and will be discharged through the pipe 18 and the manifold pipe 5 into the portion of division B which is bounded by the partitions 4, 9 and 10. The pump thus causes a constant circulation of the water from the first-mentioned portion of division B to the second-mentioned portion thereof and back again. By reason of the velocity thus imparted to the water in division B said water abstracts from the flue gases a greater percentage of heat units than would otherwise be the case. The velocity of the water in the inlet and outlet divisions is due to the pressure of the source of supply, whereas the velocity of the water in the intermediate division is due partly to the pressure of the source of supply and in part to the action of the pump 16.

The pipes 3 may be kept free from accumulations of soot by any suitable means such as scrapers 20 of the common form, said scrapers being moved up and down the pipes 3 by suitable mechanism, as, for example, that usually employed for the purpose, said mechanism being indicated at 21 in Fig. 2. Solids precipitated from the water in the economizer may be discharged through a blow-off valve 22 of common construction.

We claim as our invention:

1. A water-heater comprising water-containing means having an inlet and an outlet, and means connected to said water-containing means at points between the inlet and the outlet for drawing water from a portion of said water-containing means and returning said water to another portion of said water-containing means.

2. A water-heater comprising water-containing means consisting of an inlet division, an outlet division, and an intermediate divi-

sion, and means connected to said intermediate division for drawing water from said intermediate division and returning it to said intermediate division.

3. A water-heater comprising a plurality of sections, each consisting of a top box, a bottom box, and pipes connecting said boxes, said sections being compactly grouped side by side, a transverse partition within said top boxes, water inlet means, and means for moving the water from the space at one side of said partition to the space at the other side of said partition and back again. 75

4. A water-heater comprising a plurality of sections, each consisting of a top box, a bottom box, and pipes connecting said boxes, said sections being compactly grouped side by side, a transverse partition within said top boxes, water inlet means, water-conducting means extending from points at one side of said partition to points at the other side of said partition; and means for moving water through said water-conducting means. 85

5. A water-heater comprising a top box, a bottom box, and pipes connecting said boxes; a transverse partition within said top box; water inlet means; water-conducting means extending from a point at one side of said partition to a point at the other side of said partition; and means for moving water through said water-conducting means. 90

6. A water-heater comprising a top box, a bottom box, and pipes connecting said boxes; a transverse partition within one of said boxes; water inlet means; a water-forcing device; a pipe connecting the suction side of said device with said divided box at one side of the partition; and a pipe connecting the discharge side of said device with said divided box at the other side of the partition. 100

7. A water-heater comprising a top box, a bottom box, and pipes connecting said boxes; a transverse partition within said top box; water inlet means; a pump; a pipe connecting a suction side of said pump with said top box at one side of said partition; and a pipe connecting the discharge side of said pump with the top box at the other side of said partition. 110

8. A water-heater comprising water-containing means consisting of an inlet division to receive water under pressure, an outlet division and an intermediate division, a water-forcing device, a pipe connecting the suction side of said device with one portion of said intermediate division, and a pipe connecting the discharge side of said device with another portion of said intermediate division whereby the operation of the water-forcing device causes an increase in the velocity of the water in the intermediate division. 125

9. A water-heater comprising water-containing means consisting of an inlet division to receive water under pressure, an outlet division and an intermediate division, 5 said intermediate division comprising a plurality of sections each consisting of a top box, a bottom box, and pipes connecting said boxes, a transverse partition within said top boxes, a water-forcing device, a 10 pipe connecting the suction side of said device with said top boxes at one side of the

partition, and a pipe connecting the discharge side of said device with the top boxes at the other side of said partition.

In testimony whereof we affix our signatures in presence of two witnesses.
